UNITED STATES PATENT OFFICE.

ANTON LIJESKE AND FRANK BALCERZAK, OF MILWAUKEE, WISCONSIN.

OIL BURNER.

Application filed November 22, 1923. Serial No. 676,375.

To all whom it may concern:

Be it known that we, ANTON LIJESKE and FRANK BALCERZAK, both citizens of the United States, and residents of Milwaukee, in the county of Milwaukee and State of Wisconsin, have invented certain new and useful Improvements in Oil Burners; and we do hereby declare that the following is a full, clear, and exact description thereof.

10 This invention relates to oil burners and is particularly directed to an oil burner adapted to be positioned within a furnace such for instance as the domestic type of furnace, although the burner may be used in 15 other capacities.

Objects of this invention are to provide an oil burner in which small supply nozzles or tiny apertures for the delivery of oil will be avoided, in which a large delivery opening is provided and is yieldingly closed by a valve adapted to prevent the entrance of scale or trash which may fall upon such delivery portion, and which insures an even distribution of oil completely 25 around the delivery portion.

Further objects are to provide an oil burner in which a burner plate is provided for permitting any desired rate of combustion, in which an air preheating shell 30 devoid of relatively constricting air passages is provided, and in which a plurality of flame baffles or deflector members are provided, which may be independently removed or renewed without disturbing other portions 35 of the burner.

Further objects are to provide an oil burner in which the parts are formed from simple castings and in which the parts are so constructed that machine work is avoided 40 and attaching bolts are not required, but instead in which the successive portions are formed with interengaging parts so that they may be most readily assembled and removed for cleaning or removal.

45 An embodiment of the invention is shown in the accompanying drawings, in which:

Figure 1 is a vertical sectional view through the burner.

Figure 2 is a horizontal sectional view 50 on the line 2—2 of Figure 1.

Figure 3 is a plan view of the burner plate and a portion of the base.

The oil burner comprises a base which 55 consists of a centrally located disk 1 provided with an upstanding rib 2 and supported by means of a plurality of radially

extending spokes 3 from an outer ring 4. This outer ring 4, as may be seen from Figure 3, is provided with a plurality of inwardly projecting lugs or ears 5. The centrally located disk 1 is provided with upstanding projections 6 upon which a burner plate is adapted to rest. The burner plate 7 is a separate and distinct casting and consists of a circular disk like member provided with a centrally located upstanding standard 8 which has a centrally located hole 9 therethrough. If desired, this standard may be provided with an enlarged recessed upper portion adapted to receive the disk 10 of a valve whose stem 11 loosely fits within the hole 9 therethrough. This burner plate is further provided with a series of concentric ribs 12 which surround the standard 8 and form a series of grooves 75 in successively elevated tiers. A convenient way of attaching the burner plate to the disk 1 of the base is by means of a threaded nipple 13, as illustrated in Figure 1,—the disk 1 being centrally apertured and receiving the supply pipe 14. The outermost of the grooves formed in the burner plate 7 has projecting thereinto an upstanding overflow pipe 15 which extends above the bottom of the groove but terminates short of 80 the upper end of the outermost ribs 12.

A cylindrical member 16 surrounds the burner plate and is spaced therefrom. The lower end of this member fits outside of the rib or ridge 2 of the base and is positioned 85 thereby. A surrounding air preheating shell is provided with outer and inner cylindrical walls 17 and 18, respectively,—the lower end of the outer wall resting within the outer ring 4 and upon the lugs 5. The inner and outer cylindrical walls are integrally joined by a top portion 19 which is provided with an annular rib 20. It is to be noted that the inner cylindrical member is provided with a constricted portion 21. A plurality of similar deflectors 22 are positioned one above the other and above the central passageway through the cylindrical member 18. These deflectors are provided with downwardly projecting legs 23,—the lowermost of such legs resting upon the top portion 19 of the main shell and being held in position by means of the rib 20. It is to be noted that the top of each of these legs is flat and provides a shoulder upon which the leg 23 of 100 the succeeding member may rest. It is to be noted that each of the deflectors is substan-

tially dome shaped and thus positions the legs 23 of successive members and retains them against lateral motion. These deflectors are preferably apertured and the apertures of successive deflectors are arranged in stagger relation. It is to be understood that as many deflectors as needed may be employed as it is merely necessary to stand one upon the other.

- 10 The operation of the apparatus is as follows:—Oil is supplied through the feed pipe 14 and the combustion is started in any desired manner. The oil flows upwardly through the hole 9 in the standard 8 and 15 slightly raises the valve 10. This valve, it will be noted, causes the oil to uniformly flow over the entire upper marginal edge of the standard 8 and thus causes a sheet of oil to flow downwardly over the outer surface 20 of such standard and into the first groove. Thereafter, any oil that is not consumed at this point flows over into the next groove and if it should happen that all of the oil has not yet been consumed, such remaining 25 oil will flow to the outermost groove. If, for any reason, the fire should go out, the oil in the outermost groove will flow into the overflow pipe 15 and actuate any of the usual automatic cutoff devices.
- 30 It is to be noted that the pipe 15 projects above the bottom of the outermost groove so that such outermost groove may be used as one of the grooves for holding oil, which is being burned in the same capacity as any 35 of the other grooves independently of the overflow function furnished by the pipe 15, as such device does not function or play any part in the operation of the burner until the height of the oil in the outermost groove 40 exceeds a predetermined value.

It is to be noted that the air passes upwardly freely between the ring 4 and the centrally located disk 1. It is guided between the cylindrical member 16 and the 45 cylindrical wall 17 of the enclosing shell. It is preheated, as these parts actively absorb heat in the normal operation of the burner, and is deflected downwardly by the inner cylindrical member or wall 18. The 50 preheated air then flows across the burner plate and towards the center thus picking up vaporized oil and entering into the combustion thereof. The products of combustion pass upwardly through the interior of 55 the cylindrical portion 18 and upwardly through the constricted portion, such constricted portion insuring a rapid travel of the burning gases and causing a smokeless flame to be projected upwardly beyond the 60 outer shell. This flame is not allowed to contact directly with the furnace walls but strikes the deflectors 22 and passes laterally therefrom and also upwardly through the apertures. The staggered arrangement of 65 successive apertures prevents any tongues of

flame from passing directly through the apertures by causing a diffused and widely distributed flame to be produced.

It is to be noted that an oil burner has been provided in which minute distribution 70 nozzles for the oil are wholly avoided, and in which a relatively large oil hole for the incoming fuel is provided, thus guarding against inadvertent clogging of the apparatus. Further, this clogging is guarded 75 against by provision of the valve 10 which, it will be noted, prevents any falling scale or trash from entering the hole 9 in the centrally located standard 8.

It will further be seen that each of the 80 several parts composing the burner may be most readily cast as they are of simple formation and do not require elaborate moulding operations for their production.

It will further be seen that the successive 85 grooves formed as distinct entities in the burner plate permit any rate of combustion within the limits of the apparatus to be attained, that is to say, if a small amount of oil only is supplied the device, such oil will 90 be distributed over the central standard and will fill only the first of the concentric grooves evaporating at this point, burning, and mixing with the heated air. If a greater flow of oil is given the device the 95 next groove will also fill with oil and a more extensive burning oil surface will be presented to the incoming highly heated air. Obviously, the number of grooves could be varied to provide an apparatus of any desired capacity.

Although the invention has been described in considerable detail, it is to be understood that the invention may be variously embodied and is, therefore, to be limited only as claimed.

We claim:

1. An oil burner comprising a burner plate having an upstanding, substantially centrally located, apertured, oil supply 110 standard and having a series of grooves surrounding said standard and arranged in successive tiers, a shell surrounding said plate and extending upwardly and having a downwardly turned central shell terminating above said plate, and a plurality of independent apertured deflectors positioned one above the other and carried by the upper portion of said shell.

2. An oil burner comprising a burner plate having a substantially centrally located upstanding oil supply standard having a hole therethrough, a valve carried thereby and adapted to yieldingly cover the upper end of said hole and to cause the oil to evenly flow over the sides of said standard, said plate having a series of ribs arranged in successively elevated tiers and surrounding said standard, a relatively short upstanding ring surrounding said 120

plate, a shell surrounding said ring and spaced therefrom and having a downwardly extending portion terminating above said plate, and a plurality of independently removable, apertured deflectors carried by said shell with the apertures arranged in staggered relation.

3. An oil burner comprising a base member having an outer ring and an inner disk 10 connected thereto by spaced arms, a burner plate carried by said disk and having an upstanding, centrally apertured standard and a plurality of surrounding grooves arranged in successively elevated tiers, a relatively short cylindrical member carried by 15 said disk and extending upwardly above said burner plate, a shell having spaced inner and outer cylindrical walls with the outer wall supported by said ring and joined integrally and continuously to the inner cylindrical wall, said inner wall having a contracted portion and extending downwardly and terminating above said burner plate, a plurality of apertured deflectors adapted to be positioned one above the other and to be carried by the upper side of said shell directly above the opening through the inner cylindrical portion thereof, such shell having a ridge on its upper side and said deflectors having downwardly extending legs adapted to rest one upon the other with the lowermost of said legs resting upon said shell and guided by said ridge.

4. An oil burner comprising a base member having an outer ring and an inner disk 20 connected thereto by spaced arms, a burner

plate carried by said disk and having an upstanding centrally apertured standard and a plurality of surrounding grooves arranged in successively elevated tiers, a relatively short cylindrical member carried by 35 said disk and extending upwardly above said burner plate, a shell having spaced inner and outer cylindrical walls with the outer wall supported by said ring and joined integrally and continuously to the inner cylindrical wall, said inner wall having a contracted portion and extending 40 downwardly and terminating above said burner plate, a plurality of apertured deflectors adapted to be positioned one above the other and to be carried by the upper side of said shell directly above the opening through the inner cylindrical portion thereof, such shell having a ridge on its upper 45 side and said deflectors having downwardly extending legs adapted to rest one upon the other with the lowermost of said legs resting upon said shell and guided by said ridge.

In testimony that we claim the foregoing we have hereunto set our hands at Milwaukee, in the county of Milwaukee and State of Wisconsin.

ANTON LIJESKE.
FRANK BALCERZAK.
